ELECTRICAL TERMINAL

James Edward Lynch, Harrisburg, and Dexter Wyman Erline, Lancaster, Pa., and Ronald Charles Morehart, Columbia, Nebr., assignors to AMP Incorporated, Harrisburg, Pa.

Continuation-in-part of design application Ser. No. 5,481, Jan. 19, 1967. This application Apr. 19, 1968, Ser. No. 11,533

Term of patent 14 years

Int. Cl. D13—03

U.S. Cl. D26—1

FIG. 1 is a top perspective view of an electrical terminal showing our new design;

FIG. 2 is a top plan view thereof with the post broken away for ease of illustration;

FIG. 3 is a side elevational view thereof;

FIG. 4 is a front end view thereof;

FIG. 5 is a rear end view thereof;

FIG. 6 is a top perspective view of a modified form thereof, with the post broken away for ease of illustration;

FIG. 7 is a top plan view thereof;

FIG. 8 is a side elevational view thereof;

FIG. 9 is a front end view thereof; and

FIG. 10 is a rear end view thereof.

This is a continuation-in-part of design application Ser. No. 5,481, filed Jan. 19, 1967, now abandoned.

We claim:

The ornamental design for an electrical terminal, as shown and described.
